UNITED STATES PATENT OFFICE.

THOMAS OLIVER, OF TORONTO, ONTARIO, CANADA.

RAIL-CLAMP WHEEL-STOP.

1,096,121.

Specification of Letters Patent.

Patented May 12, 1914.

Application filed December 16, 1912, Serial No. 737,027. Renewed November 8, 1913. Serial No. 799,993.

To all whom it may concern:

Be it known that I, THOMAS OLIVER, of the city of Toronto, in the county of York, in the Province of Ontario, Canada, have 5 invented certain new and useful Improvements in Rail-Clamp Wheel-Stops, of which the following is the specification.

My invention relates to improvements in rail clamp wheel stops, and the object of the 10 invention is to devise a simple form of stop, which may be adjustably secured in any position on the ball of the rail and it consists essentially of two opposing members meeting over the center of the ball of the 15 rail and extending upwardly therefrom and having hooked lower ends extending around each side of the ball of the rail so as to bear against each side of the rail web and having alined orifices extending 20 through the vertical portion thereof, a headed pin extending through such orifices having a key slot in the opposite end thereof, and a wedge key inserted in the slot so as to bear against the adjacent vertical 25 member as hereinafter more particularly explained by the following specification.

Figure 1, is a general perspective view of my device as applied to a rail. Fig. 2, is a side elevation showing a wheel in position 30 against the stop. Fig. 3, is a detail of one of the stop members and headed pin partially inserted in the orifice thereof. Fig. 4, is a perspective detail of the opposing member. Fig. 5, is a detail of the securing 35 key.

In the drawings like letters of reference indicate corresponding parts in each figure.

A is a portion of a rail and A' is a car wheel supported thereon.

40 B is my stop comprising the vertical opposing members B' and B² and hook portions B³ extending around the ball A² of the rail A, so that the vertical portions B' and B² meet and extend vertically over the 45 center of the rail.

B⁴ and B⁵ are alined orifices extending through the vertical portions of the members B' and B² in proximity to the hook ends thereof.

50 B⁶ is a pin extending through the orifices B⁴ and B⁵ having a head B⁷ which when

the pin is in position, bears against the outer face of the vertical portion B'. The vertical portion B² is preferably provided with a boss B⁸ through which the orifice B⁵ extends. The opposite end of the pin B⁶ is provided with a horizontal orifice B⁹. 55

B¹⁰ is a locking wedge key extending through the orifice B⁹ and wedging against the outer face of the boss B⁸, so as to draw 60 the pin B⁶ tight into position and the members B' and B² together, so that the hooked portions B³ grip the ball of the rail.

It will be understood that my stop is particularly adapted for light work such as the 65 dumping cars of a dredge where a simple form of stop is required which is readily adjustable to the required position to stop the cars at any particular point.

What I claim as my invention is: 70

1. A wheel chock, for railway rails, including complemental clamp-members having lower rail-engaging ends and upstanding portions, one of said upstanding portions having a lateral offset or boss, said 75 upstanding portions having coincident passages therethrough, said lateral offset or boss being provided with a passage in continuation of the aforesaid passages, a headed pin inserted within said passages, 80 including the passage-continuation of the boss or offset, and means for the retention of said headed pin in locked position in said upstanding members.

2. A wheel chock for railway rails, including complemental clamp members having lower rail-engaging ends and upstanding portions, one of said upstanding portions having a lateral offset or boss said upstanding portions having coincident 90 passages therethrough, said lateral boss or offset being provided with a passage in continuation of the aforesaid passages, a headed and slotted pin insertible within said passages including the passage continuation 95 of said boss or offset, and a wedge shaped key insertible through the slot in said pin.

THOMAS OLIVER.
